CLAIM

The ornamental design for a headset for telephone as shown and described.

DESCRIPTION

FIG. 1 is a Top Front and Right Perspective view of a headset for telephone showing the new design;

FIG. 2 is a Front elevational view thereof;

FIG. 3 is a Rear elevational view thereof;

FIG. 4 is a Left elevational view thereof;

FIG. 5 is a Right elevational view thereof;

FIG. 6 is a Top view thereof; and,

FIG. 7 is a Bottom view thereof.

The broken lines depict portions of the headset for telephone that forms no part of the claimed design.
